WILLIAM STROBRIDGE, OF SYRACUSE, NEW YORK, ASSIGNOR TO UNITED STATES
HOFFMAN MACHINERY CORPORATION, OF NEW YORK, N. Y., A CORPORATION OF
DELAWARE

OPERATOR'S BENCH

Application filed March 7, 1931. Serial No. 521,029.

This invention pertains to benches and actuating devices associated therewith designed to be utilized in connection with operator operated mechanisms, the actuation 5 of which latter by the actuating devices directly accomplishes, or initiates movement of certain power means to accomplish, the desired operation.

More specifically, the structure is intended 10 for use in connection with garment pressing machines and the like wherein foot actuated levers are employed to effectuate or bring about certain operations. With machines of such type, that is where the operator is standing and depressing one lever after another, and consequently raising one foot and then the other, the operation becomes fatiguing, and particularly so to women. The present invention provides means whereby the operator may remain seated and readily bring 15 any one or another, and in some instances two, of the actuating devices, and consequently the corresponding lever or levers, into operation to effectuate the desired result.

The invention comprehends and includes any combined bench or seat and actuating device which may be positioned with reference 20 to a machine with a view of bringing such devices into cooperative relation with the operating mechanism of the machine.

Furthermore, the invention includes means for locking the bench to the machine, said means being such that the locking is effected 25 automatically as the bench is positioned and is likewise readily releasable by the operator.

One embodiment of the invention is disclosed in the annexed drawings wherein:

Figure 1 is a perspective view of the bench 30 with the actuating levers carried thereby in operative relation with the machine levers, the latter being broken away, and the figure also disclosing the locking or attaching means;

Figure 2, a side elevation with parts in sec-

tion showing the bench attached to a machine frame and the lever of the machine and bench in operative relation;

Figure 3, a similar view with the bench in its detached position;

Figure 4, a top plan view of the structure with parts in section, the bench being locked to the machine frame; and

Figure 5, a vertical sectional view on the line V—V of Figure 2.

In the drawings, 1 denotes a portion of the main frame of a garment pressing machine having four levers 2, 3, 4 and 5 fulcrumed upon a shaft, as 6, the latter being secured in the frame 1. The levers are provided at their outer ends with the usual foot piece 7. They are also connected to various operating elements, not shown, through draw links designated generally by 8 throughout the series, which links lead to operative parts such as 60 head closing and opening devices; heavy pressure applying means; and steaming and vacuum valves. It will be understood, of course, that in the broader aspect of the invention, as above set forth, the lever 2, or a 65 plurality of levers, may be present in the machine.

Normally the levers, which will hereinafter be denominated "machine levers" are held in their elevated position by a spring, as 9, one 70 under each lever. The arrangement so far described is common in garment pressing machines on the market.

The machine frame 1, at each side thereof, and adjacent the forward portion (see more 75 particularly Fig. 4), is provided with a fixed outwardly extending stud, the studs being numbered 10 and 11 respectively. These studs, as will be apparent, provide one element of the locking means or mechanism employed to hold the workman's bench or seat in proper relation to the machine levers. The bench in the instant case may be said to comprise a platform 12 secured to a carriage, denoted generally by 13, preferably formed 80

from pipes and fittings. The forward pipe element, denoted by 14, is employed, as will hereinafter appear, as a fulcrum for certain operating elements.

5 Mounted upon the rear portion of the platform 12 is a bench or seat 15.

Fulcrumed upon shaft 14 is a lever of the first order, the rear arm 16 whereof extends upwardly through the platform 12 and is provided with a foot piece 17. Stop lugs 18 carried by the arm 16 extend laterally from said arm and abut the under face of the platform 12 and prevent the lever from swinging upwardly too far. The second arm of the lever 15 16^a, which extends forwardly of the shaft 14, has formed integrally therewith a cross bar or member 19 and extending forwardly from said bar are two arms 20 and 21. Said arms are spaced apart a distance sufficient to allow

20 the arms to engage the studs 10 and 11 respectively when the bench and the operating parts carried thereby is pushed up into position with reference to the machine. Each of the arms 20 and 21 is provided on its under

25 face, at the forward portion thereof, with a notch 22 and a camming surface as 23. The operation is such that as the bench is pushed from the position shown in Figure 3 to that of Figure 2 the camming surface 23 will first contact the pins or studs 10 and 11, rocking the forward member 16^a of the lever upwardly and then allowing the arm to drop downwardly so that the notches 22 will engage the studs and hold the bench in locked relation to the machine frame.

30 Fulcrumed upon the shaft 14 are a plurality of levers, designated by 24, 25, 26 and 27, held in proper spaced relation with reference to each other and to the machine levers 2 to 40 5, inclusive, by spacing collars, denoted throughout by 28. These levers, which will hereinafter be termed "operating levers", are of the second order and are given a substantially L-shaped form. The lower rearwardly extending portion of each lever is bifurcated and a roller 29 is mounted between the bifurcated portions at the bend of the lever;—the roller, when the parts are positioned, contacting the upper face of the machine lever with reference to which it is positioned. Each of the levers 24 to 27 respectively is provided at its upper end with a foot piece 30, said foot piece, when the parts are brought to locked and operative position, as shown in Fig. 2, extending upwardly within easy reach of the foot of the operator. This is due to the fact that the machine levers act as camming surfaces with reference to the operating levers and tend to throw

45 55 60 65 the same upwardly to a sufficient degree to render them readily accessible when the bench is locked to the machine frame.

When it is desired to remove the bench from the machine it is only necessary that the operator place his heel upon the foot piece 17

and thus rock the locking mechanism comprising the lever 16, 16^a, bar 19, and arms 20 and 21, so as to disengage the arms from the studs or pins. The operator may then by pushing against frame 1 readily move the bench away from the machine and immediately have the machine available for operation in the usual manner.

70 As the bench is moved outwardly from the machine the operating levers 24 to 27 inclusive will swing forwardly and will come in contact with the stop bar 19 and be held in the position shown in Figure 3 by said bar. The bar, of course, which is connected to the lever 16, 16^a, cannot move downwardly beyond the position shown in Figure 3 by reason of the fact that the stops 18 will be in engagement with the underface of the platform 12.

75 80 85 From the foregoing it will be seen that the bench, when rolled up to the machine, will be automatically locked thereto and the operating levers brought into cooperate relation with the machine levers. The operator may then depress any one of said operating levers to bring about the desired operation in the machine.

90 95 In the claims the terms "bench"; "operator's bench"; or "mobile bench" are intended to cover any bench broadly, unless by reason of the context of the claims another construction is indicated.

100 So too the term "carriage" is to be generally considered and to be understood as including the framework, the wheels, and the superstructure.

What is claimed is:

1. In combination with an operator's bench, means carried thereby for locking the same in working relation with a machine having at least one operator operated device for initiating or effectuating an operation; and means also carried by the bench and adapted to extend into operative relation to said device and likewise to such position that it may be actuated by the operator for moving the operator operated device.

105 110 115 2. A structure as set forth in claim 1, wherein the bench is mounted on a carriage.

3. A structure as set forth in claim 1, wherein the locking means comprises a pivoted member automatic in its engagement with a fixed portion of the machine when the bench is moved into operative position with reference to the machine and means is provided whereby the operator while occupying the bench may release the same.

120 125 130 4. In combination with an operator's bench, gravitating locking means carried thereby and cooperating with a fixed portion of a machine to be operated to lock the bench and machine together, said machine having at least one operator operated device for initiating or effectuating an operation; and means also carried by the bench and extend-

ing into operative relation to said device and likewise to such position that it may be actuated by the operator for moving the operator operated device.

5. 5. A structure as set forth in claim 1, wherein the means for locking the bench to the machine includes a lever of the first order pivotally mounted on the bench with a foot piece extending upwardly from the inner end thereof the opposite end being provided with means to engage a fixed portion of the machine. 70
75

6. In combination with an operator's bench, a lever of the first order fulcrumed thereon with one end in position where it may be readily reached by the operator, the opposite end being provided with means to engage a fixed portion of a machine to be operated; and at least one lever of the second order fulcrumed upon the bench, said lever, when the carriage is brought to its locked position with reference to the machine to be operated, overlying an operating element on said machine. 80
85

7. In combination with an operator's bench adapted to be connected to a machine to be operated and having at least one outwardly extending pedal lever, for initiating or effectuating an operation; means for securing said bench to the machine to be operated; and means carried by the bench and overlying the pedal lever when the bench is locked to the machine; said means serving, when depressed by the operator, to actuate the pedal lever. 90
95

8. In combination with a mobile operator's bench adapted to be connected to a machine to be operated, the latter having at least one foot lever for initiating or effectuating an operation in said machine; means carried by the bench for locking the latter to the machine; a lever fulcrumed upon the bench and overlying a foot lever carried by the machine aforesaid; and a roller carried by said first named lever and bearing upon the upper surface of the foot lever when the bench is locked in place. 100
105
110

9. In combination with an operator's bench, a plurality of operating levers of the second order pivotally mounted at the forward end thereof, the upper end of the levers extending into a position where they may be readily actuated by the operator, the opposite ends of said levers being adapted to overlie a plurality of machine levers extending outwardly from a machine to be operated, said machine levers underlying the first named levers; means for securing the bench to the machine to be operated; and means carried by said bench securing means for limiting the downwardly swinging movement of the operating levers when the bench is detached from the machine. 115

10. In combination with a bench, a lever of the first order pivotally secured to the

bench and provided with outwardly extending arms, said arms at their outer ends each being provided with a notch; and a plurality of levers of the second order likewise pivotally supported by the bench, said levers being adapted to overlie a plurality of machine levers to be actuated and serving to actuate the latter when the former are depressed, and the notches being designed to engage fixed elements carried by the machine to lock the bench to the machine. 75

11. In combination with an operator's bench, means carried thereby for locking the same in working relation with a machine having at least one operator operated device for initiating or effectuating an operation; means also carried by the bench and extending to such position that it may be actuated by the operator for moving the operator operated device; and means for locking the bench to the machine in working relation; said means containing a lever of the first order fulcrumed upon the bench, the inner end of the lever extending upwardly in position where it may be readily pressed downwardly by the operator, stops to limit the upward movement of said lever, and means at the outer end of the lever to engage a fixed portion of the machine to be operated. 80
85
90

12. In combination with an operator's bench, a shaft extending transversely of the forward portion thereof; a plurality of operating levers of the second order fulcrumed upon the shaft, said levers being adapted to overlie machine levers of a machine to be operated; a roller carried by each of said actuating levers and contacting the machine levers; a lever of the first order fulcrumed upon the shaft, the inner upper end of said lever extending upwardly within easy reach of the operator's foot; stops carried by said lever for limiting its upward movement; a cross bar carried at the forward end of the outer arm of the lever, said bar underlying the operating levers; and a pair of arms extending forwardly from said bar, each bar adjacent its outer end and at its lower face being notched and adapted to engage a pair of studs extending from the machine frame when the bench is moved forwardly into operative relation with the machine. 95
100
105
110

13. A structure as set forth in claim 12, wherein the forward under faces of the arms are upwardly inclined from the notches whereby the arms will be automatically raised through contact of such inclined faces with the studs. 115
120

14. In combination with an operator's bench, a lever carried by the bench for actuating a foot lever of a machine to be operated; and means also carried by the bench for locking the bench to the machine, said means, in part at least, underlying the actuating lever and forming a rest therefor when the

bench is moved out of operative relation with the machine.

15. A structure as set forth in claim 14, wherein the foot lever is formed with an upwardly inclined face and the actuating lever carries a roller which rides up on said face as the bench is brought into operative relation with the machine, whereby the actuating lever is rocked in an upwardly direction away from the rest.

In testimony whereof I have signed my name to this specification.

WILLIAM STROBRIDGE.
